UNITED STATES PATENT OFFICE.

WILLIAM H. BROCK, OF CORONA, ASSIGNOR OF ONE-FOURTH TO JOHN W. ALEXANDER, OF NEW YORK, N. Y.

CHAIN-WRENCH.

SPECIFICATION forming part of Letters Patent No. 247,987, dated October 4, 1881.

Application filed August 5, 1881. (No model.)

To all whom it may concern:

Be it known that I, WILLIAM H. BROCK, a citizen of the United States, residing at Corona, in the town of Newtown, in the county 5 of Queens, in the State of New York, have invented a new and useful Chain-Wrench, of which the following is a specification.

The nature of my invention consists of certain improvements in chain-wrenches used for 10 tightening or loosening nuts, joints in pipes, and other like resistants; and the objects of my improvements are, first, the construction of a wrench wherein is found the possibility of an extra wrench ready for use and without 15 additional cost whenever, by the breakage or wearing out of the teeth of the jaws, a new wrench is required; second, to provide a facile means of connection of chain with either face of cheek and its ready readjustment in case 20 of breakage of link or otherwise; third, to provide a method for locking and holding taut the chain when power is applied in slots provided 25 in each of the faces of the shank; and, fourth, provision for detaching the jaws from the shank for repairs, so that when restored or another set substituted the whole appliance is as new at little attendant cost.

Figure 1 of the accompanying drawings is 30 a central vertical section of the tool in position for operating. Fig. 2 is a side view, and Fig. 3 a front view, of the entire tool. Fig. 4 represents the end view of the invention, and Fig. 5 a side view of the jaw.

Into slots in the cheeks K of the head of the shank or handle A, Fig. 2, are carefully fitted 35 the jaws B, wherein they are tightly held, so as to prevent all lateral motion. The jaws are firmly secured to the shank and held in place by the assembly-bolt C, provided with a head 40 and nut, which passes through the head of the shank from one jaw to the other, as shown in Fig. 3.

The chain M in this invention is made fast 45 to the shank by means of the pivot D, Fig. 2, passing from one cheek to the other through the end link of the chain.

It is evident by this novel combination that any link of the chain can be thus utilized as emergency by breakage of link or otherwise

demands. The accompanying drawings show 50 that provision is made for attaching chain to either face of the shank corresponding to the edge of the jaw to be applied.

Each face of the shank is made with an elliptical or link-shaped slot, H, Fig. 3, of a size 55 capable of receiving a link of the chain in its length and breadth, but which is narrowed at the top and bottom, so as at these points to allow only of the introduction of the links edge-wise. By this device, when a link of the chain 60 is dropped into the slot it is held in position and prevented from moving upward by the resistance offered by the introprojecting sides, Fig. 3, above it.

It is also apparent that the increased width 65 of the metal at the lower end where the pivot D passes adds materially to the strength of the cheeks at that point and to their resisting power.

Both edges of each of the jaws are toothed, 70 and by simply transposing the pivot D to the other cheek of shank, Fig. 1, and connecting chain, as before described, either edge of the jaw may be applied.

It is evident that by withdrawing the bolt 75 C the jaws may be easily removed from the shank for any purpose desired.

My wrench, when operated, is placed with the teeth of one edge resting upon the resisting object G, with chain attached to corresponding side of shank, as in Fig. 1. The chain is passed under and around the object and locked by dropping the link-pendant opposite the slot into it. The force is applied by raising up the handle or shank. The result is limited only by the power applied and the strength 85 of the materials.

Aware that prior to my invention wrenches have been made for purposes herein specified, in which the combination of shank, jaw, and 90 chain exist, I therefore do not claim such a combination, broadly; but

What I do claim as my invention, and seek to secure by Letters Patent, is—

1. The combination, in a chain-wrench, of 95 the shank A, provided with two pivot-holes, as herein shown, for the interchangeable adjustment of chain from one face to the other,

corresponding to edge of jaws applied, jaws B, the pin D, and chain M, substantially as set forth.

2. The combination, in a chain-wrench, of
5 two detachable double jaws, B, with both edges
of each jaw serrated or toothed, the assembly-
bolt C, the shank A, with slotted cheeks for

holding the jaws and slotted faces for locking
the chain, the pin D, and chain M, substan-
tially as and for the purposes herein described. 10

WILLIAM H. BROCK.
